OVERCAP FOR A PRESSURIZED CAN

Peter P. Gach, Evansville, Ind., assignor to Sunbeam Plastics Corporation, Evansville, Ind., a corporation of Indiana

Filed Apr. 23, 1965, Ser. No. 84,942

Term of patent 14 years

(Cl. D58—26)

FIG-1-

FIG-5-

FIG-2-

FIG-3-

FIG-4-

FIG. 1 is a top plan view of an overcap for a pressurized can, embodying my new design;

FIG. 2 is a side elevational view;

FIG. 3 is a front elevational view;

FIG. 4 is a bottom plan view; and

FIG. 5 is a vertical sectional view thereof taken along the line 5—5 of FIG. 1.

I claim:

The ornamental design for an overcap for a pressurized can, as shown.
